PERCUSSION EXTRACTING DEVICE

Oscar Luis Caviglia, Buenos Aires, Argentina

Application October 28, 1941, Serial No. 416,873

5 Claims.

(Cl. 32—40)

This invention relates to a percussion extractor device, and more particularly to a percussion extractor device for use in dentistry.

An object of the invention is to provide a unit formed by a suitable combination of elements, which is easy to use, safe to operate in connection with the extraction of bridges, bands, crowns and the like in dentistry, through the simple actuation of a trigger.

The device which is the subject of the present invention is constituted mainly by a hooking element or means removably connected to a stem or guide and ending in a head having a larger section, where a hammer exerts the stress, said hammer being coaxially mounted on said stem and actuated by a spring, the assembly being operated and adjusted at will, so as to provide a range of percussion intensities.

Together with the main feature, the device presents other features, such as the inclusion of shock absorbing means, means for fixing the correct initial and operative positions, and others which will become apparent from the course of the present specification.

In order that the invention may be readily understood and carried into practice, the same has been illustrated by way of example in the accompanying drawing, wherein:

Figure 1 is an external view of the device;

Figure 2 is a longitudinal section of the same device in the final position or immediate to the stroke;

Figure 3 is a view similar to Figure 2, but showing the device during a phase of the charging operation;

Figure 4 is a view similar to Figure 3, but showing the device completely charged and ready for use;

Figure 5 is a plan view of Figure 1;

Figure 6 is a sectional view along the line *a—b*;

Figure 7 is a sectional view along the line *c—d*.

The same reference characters indicate like or corresponding parts or elements throughout the different figures.

The device illustrated comprises a tubular supporting and guiding casing 1, provided with a front cover 2 and a rear cover 3.

Cover 2 acts as a guide for the free linear play of a stem or shank-member 4 which extends out of said cover through an axial perforation therein. The free end of said shank 4 carries a hook member 5, ending in a curved end 6 and provided

with a tooth 7 serving to hold the dental object to be extracted.

The front end of said shank 4 includes an annular flange 8 acting as an actuating grip for disengaging said shank out of the tubular casing 1, in the manner and for the purpose to be described later.

The shank 4 is inserted in a hammer or core member 9 in a manner so as to have free linear play, the revolution surface of said hammer 9 being provided throughout its extension with a plurality of notches defining annular toothed zones 10, suitably equidistant, said notches being engaged by a pawl 11 of a trigger 12, linked to a forked support 13 integral with the casing 1. Said trigger 12 is opposed by a laminar spring 14, the pawl 11 entering into said casing through an orifice made therein.

The shank 4 is kept connected to the toothed core member or hammer 9 by means of a member or rear head 15, against which said hammer strikes in its backward motion, said hammer exerting upon the shank the backward stress in the manner and for the purpose to be indicated hereunder.

The hammer 9 is actuated by an expansion spring 16, the last turn of which is located in a socket provided in the front head thereof, while the opposite end of said spring is secured to the front face of the cover 2.

The device also includes, on the inner portion of cover 3, an expansion spring 17 of the usual frusto-conical type, constituting the means for absorbing the shock of the head member 15 against the cover at the end of its backward stroke; it also includes on the front end of shank 4, a radial stop 18 operating in a slot 19, passing axially through the cover 2, including a plurality of complementary axial slots 20, said slots constituting the access means to the stop 18, so as to establish the blocking action of the rotary axial play of the shank 4 during the operation of hooking the device to the object to be extracted.

The reason for including this plurality of annular toothed zones 10 in the hammer member 9, is to enable the regulation of the traction force to be exerted by the hook 7 on the dental object to be extracted, which depends on the greater or lesser compression of the spring 16, and is subject to the engagement of the element 11 with one of said toothed annular zones, it being understood that the more advanced the hammer is within the tubular element 1, the greater the force will be.

The operation of the device is as follows: The device is charged by pulling out the shank 4 which carries the hammer 9 the latter abutting against the pawl 11, and causing the trigger 12 to move angularly on its support. The advance of the shank 4 and hammer 9 is continued to the required degree, according to the necessary tension of spring 16 and the force required to extract the dental object, at which time the pawl 11 is inserted in one of the toothed zones 10 of the hammer, for example the rear zone as shown in Figure 4 and which corresponds to the maximum force of the device, inasmuch as in this position the spring 16 is completely compressed.

Thereafter, the shank 4 is pushed in to the tubular element 1, until the stop 18 remains out of the slot 19, at which time the shank is turned until the stop thereof enters any of the slots 20, into which the shank enters with the aid of the tension of the shock-absorbing spring 17 operating on the head member 15, the shank 4 being thus prevented from turning and therefore placing the device ready for use (Figure 4). The dental object to be extracted is hooked by the tooth 7 of hook 5, and at this moment the operator presses the trigger 12, whereby the pawl 11 releases the toothed hammer 9, the spring 16 then acting against said hammer, giving the same a strong backward stroke which is transmitted to the shank 4 and consequently to the hook 7, thus causing the immediate extraction of the dental object, which may be a band, crown, bridge, or the like.

It should be clearly understood that the invention is capable of being modified in construction and detail, without departing from the scope of the invention as clearly set forth in the appended claims.

What I claim is:

1. A percussion extraction device, comprising

5 a hooking element connected to a guiding stem and ending in a fixed head, said stem being coaxially provided with a hammer having notches and a spring, said elements being housed in a casing provided with a trigger actuating in said notches, so as to provide a charge for graduating the force of the element and the stroke of extraction by the discharge of said element.

10 2. A percussion extracting device as claimed in claim 1, including means for absorbing the percussion shock.

15 3. A percussion extracting device as claimed in claim 1, including means for guiding the hooking element and means for fixing the operative position thereof.

20 4. A percussion extracting device as claimed in claim 1, in which the hooking element is removably connected to the stem of the device.

25 5. A percussion extracting device comprising a substantially cylindrical casing, a cap at each end thereof, one of the caps having a central perforation, a tool stem located and guided in the perforation of the cap, an extraction tool being removably secured to the stem, said tool having a curved end provided with a tooth, the end of the stem within the casing having an enlarged head thereon, a hammer slideable on the stem within the casing, annular notches provided along the length of the hammer, a spring around the stem and located between the perforated cap and hammer, a trigger pivoted to the casing and cooperating with the notches in the hammer to hold the spring in compressed condition, and a spring in the casing above the enlarged head on the stem for absorbing the shock of the blow delivered by the hammer to the head when the trigger is operated and transmitted along the stem to the hook on the end of the tool for extracting the object with which the hook may be engaged.

OSCAR LUIS CAVIGLIA.
